SANITARY CUFF

Vincent Muccillo, Hamilton, Ohio

Application April 19, 1944, Serial No. 531,712

5 Claims. (Cl. 2—232)

1

The present invention relates to improvements in garment constructions and is particularly directed to a sanitary cuff structure and a means for fastening said cuff to the finished edge portion of sleeves and trousers of wearing apparel.

It is an object of the invention to provide a means for securely fastening an independently formed cuff to the finished edge portion of garments to form a number of uninterrupted spaces between the cuff and the portion to thereby provide a sanitary garment construction which precludes the deposition of foreign matter, such as dirt or dust particles, between the cuff and garment portion.

Another object of the invention is to provide a fastening edge for a cuff structure which may be readily tacked to the finished edge portion of a garment.

A further object of the invention is to provide a cuff which has a simplified structure and which may be readily attached to or detached from the finished edge portion of a garment.

A still further object of the invention is to provide a tubular cuff member fastened to the edge portion of a garment which serves as a means for readily altering the length of said garment.

Other objects will be apparent from the following specification and drawings, in which:

Fig. 1 is a fragmental side elevational view of a trouser leg for a garment with my sanitary cuff positioned thereon.

Fig. 2 is an enlarged cross-sectional view taken on line 2—2 of Fig. 1.

Fig. 3 is a cross-sectional view taken on line 3—3 of Fig. 2.

Figs. 4, 5 and 6, are perspective views of the cuff shown in Figs. 1—3, in various stages of its construction.

Figs. 7 and 8 are perspective views of a modified cuff which may be applied to the garment illustrated in Figs. 1—3.

Fig. 9 is a fragmental side elevational view of a garment trouser showing a modified cuff structure.

Fig. 10 is an enlarged cross-sectional view taken on line 10—10 of Fig. 9.

Fig. 11 is a cross-sectional view taken on line 11—11 of Fig. 10.

Figs. 12 and 13 are perspective views illustrating the intermediate steps for constructing the cuff shown in Figs. 9—11.

With reference to Figs. 1—6 of the drawing the numeral 20 illustrates one leg of a trouser for a garment which has a front part 21 and a rear

2

part 22 joined together along their vertically disposed marginal edges by interior side seams 23 and 24. The lower portion 25 of this pant-shaped member is finished by turning the edge portion 26 inwardly and fastening it to the interior surface of said member by a line of stitches 27.

A cuff 28 is adapted to encircle the finished portion 25 of the member 20 and as shown in Fig. 2 said cuff is provided with an outer ply 29 and an inner ply 30, said outer ply having a continuous smooth surface and the inner ply being provided with a longitudinally disposed exterior seam 31. The cuff is fastened to the member 20 by means of stitches 32 which pass through the material of the member and the longitudinal ends of the cuff which are bound together at the seam 31. As most clearly shown in Fig. 3 a plurality of extended and uninterrupted spaces 320 are formed by the lower edge portion of the member 20 and the cuff between the fastening points 32 to thereby preclude the deposition of dust or other particles therebetween.

The manner of constructing the cuff shown in Figs. 1 and 3 is illustrated in Figs. 4—6 and consists of folding a piece of fabric material 33 with its wrong side 34 turned outwardly. The transverse ends of the material are then bound together by a line of stitches 35 and said completed band is then turned inside out as illustrated in Fig. 5 to thereby provide an inside seam 36 along the bound ends of the band. The wrong side of the band is then folded upon itself along a central fold line 37 so that the opposed longitudinal edges of the band are brought into alignment as illustrated in Fig. 6 and thereafter a line of stitches 38 is passed through said longitudinal edges to provide the exterior seam 31. The band is then rolled so that said exterior seam is brought to a position intermediate the interior ply 30 of the band and said seam is then tacked to the finished edge portion of the garment member by means of stitches 32. It will, therefore, be noted that said cuff has a tubular like structure which permits it to be rolled relative to its tacking position and said cuff, therefore, serves to lengthen the member 20 to a position indicated by the dotted lines 40 in Fig. 2 in the event of shrinkage of the garment material.

A modified form of a cuff structure is shown in Figs. 7 and 8 wherein a strip of fabric material 41 is folded upon itself and provided with an inside seam 42. The transverse edges of this cuff are then brought together and provided with an inside seam 43. The resulting structure may then be fastened to the edge portion of the mem-

ber in a manner similar to that shown in Figs. 1-3.

While the cuff 28 has been described as having a single transverse seam 36 formed therein, it is to be understood that a similar seam could be formed in the strip 33 at a point diametrically opposed to said seam as it is illustrated in Fig. 5 whereby a two-part cuff would be formed which would have the same functions as the cuff 28. Furthermore, I contemplate the interposition of snap fastener elements or buttons and button holes between the exterior seam 31 and the edge portion of the garment 20 at the tacking points 32 so that said cuff may be readily removed for cleaning purposes.

Another modification of my cuff structure is illustrated in Figs. 9-13 wherein a two-ply cuff 44 encircles the finished edge portion 45 of a trouser 46 for a garment. This trouser is provided with a front part 47 and a back part 48 which are joined along their adjacent marginal edges by interior seams 49 and 50. A cuff 44 is constructed from a front part 51 and a rear part 52 which are joined together at their transverse edges by means of folded portions 53 and 54 respectively which are folded in the side seams of the garment. In Fig. 13 is shown a cuff part such as the front part 51 wherein the longitudinal edge portions 55 and 56 are turned inwardly upon the body portion 57 so that their longitudinal margins will abut along a line 58. These margins are held together by a line of stitches 59. In constructing this cuff structure, the cuff front part 51 and the cuff rear part 52 are placed one upon the other with their joining stitches 59 exposed. The cuff parts are then laid upon the right side 60 of the garment back part 48 and, thereafter the garment front part 47 is placed upon the cuff parts with its wrong side 61 exposed. Said cuff parts are spaced away from the lower edge portions 62 and 63 of the garment parts 47 and 48 respectively and a line of stitches 64 and 65 are then run through the marginal edges of the stack. The resulting structure is then turned inside out to thereby form the inside seams 49 and 50 along the lines of stitches. The lower edge portions 62 and 63 are then turned upwardly to form the finished edge portion 45 for the garment, a line of stitches 66 being provided to hold said edge to the wrong side of the garment.

The central interior portions of the cuff parts are then tacked to the finished edge portion of the member by stitches 67 and it will be noted that this cuff structure provides a number of uninterrupted, vertically disposed spaces 68 between the member and the interior surface of the cuff and longitudinally extending between the said tacking points 67 and the side seams 49 and 50 of the garment.

What is claimed is:

1. In a trouser the combination of a leg covering member terminating in a finished edge portion, a cuff encircling the finished edge portion, and independent spaced apart means for fasten-

ing the cuff to the member whereby extended and uninterrupted spaces, opened at the top and the bottom, are formed between the edge portion and cuff and between the fastening means.

- 5 2. In a garment the combination of a pant-shaped member terminating in a finished edge portion, a cuff encircling the finished edge portion and comprising a continuous two-ply band, an interior seam joining the transverse ends of 10 the band, an exterior seam joining the longitudinal edges of the band, said exterior seam extending from the inner ply and disposed adjacent the edge portion of the member, and means for tacking the exterior seam to the edge portion 15 at a plurality of spaced apart points.
3. In a garment the combination of a pant-shaped member terminating in a finished edge portion and having opposed, interior side seams, a two-part cuff encircling the finished edge portion, the transverse ends of the cuff parts being turned inwardly and fastened in the interior side 20 seams of the member, and means for tacking the central portions of each cuff part to the finished edge portion of said member.
- 25 4. In a garment the combination of a pant-like member terminating in a finished edge portion and having a front part and a back part joined along their adjacent margins by interior seams, a two-part cuff encircling the finished edge portion 30 of the member and each part having a tubular shape and provided with a line of stitches for joining their longitudinally extending ends, said line of stitches being disposed on the side of the cuff parts adjacent the edge portion of the member, the transverse ends of said cuff parts being turned inwardly and fastened in the interior side 35 seams of the member, and means for tacking the central interior portions of each cuff part to the finished edge portion of said member.
- 40 5. In a trouser construction the combination of a leg covering terminating at its lower end in a finished edge portion, a continuous cuff encircling the lower portion of the leg covering and having its lower edge disposed flush with said finished edge, and independent spaced apart 45 fastening means disposed between the adjacent faces of the leg covering and the cuff to form extended, uninterrupted spaces, opened at the top and bottom, between said fastening means and between the adjacent faces of the leg covering and cuff.

Certificate of Correction

Patent No. 2,419,279.

April 22, 1947.

VINCENT MUCCILLO

It is hereby certified that the address of the inventor in the above numbered patent was erroneously described and specified as "Hamilton, Ohio", whereas said address should have been described and specified as *Cincinnati, Ohio*; and that the said Letters Patent should be read with this correction therein that the same may conform to the record of the case in the Patent Office.

Signed and sealed this 22nd day of July, A. D. 1947.
